[57] **CLAIM**

The ornamental design for a refrigerator with eye level controls, as shown and described.

DESCRIPTION

FIG. 1 is a perspective view of a refrigerator with eye level controls in closed condition showing our new design;

FIG. 2 is a front elevational view thereof;

FIG. 3 is a side elevational view thereof, the opposite side being a mirror image of that shown;

FIG. 4 is a rear elevational view thereof;

FIG. 5 is a top plan view thereof;

FIG. 6 is a front elevational view thereof with the door in open condition showing the eye level control panel and door interior.
